FEED WATER REGULATING APPARATUS
FOR BOILERS

William L. Hunter, Erie, Pa., assignor to Northern Equipment Company, Erie, Pa., a corporation of Pennsylvania

Application April 14, 1942, Serial No. 438,960

3 Claims. (Cl. 122—451.1)

This invention relates to feed water regulating apparatus for boilers, and more particularly to apparatus of this type which has distinct advantages when employed on marine boilers although not limited to such use.

As is well understood, it is desirable to automatically regulate the feed water supply to boilers and maintain the boiler water level within pre-determined limits. This has commonly been effected in stationary boilers by having a tube or the like in communication with the steam and water space of the boiler whereby the water level in the tube will correspond to the water level in the boiler and regulate the feed water valve in accordance with tube water level. However, such apparatus is not satisfactory for marine boilers since the tube water level is materially disturbed by the roll of the ship resulting in rapid and highly undesirable fluctuations in the amount of feed water being fed to the boiler.

I am aware that it has previously been proposed to compensate for ship roll by employing two tubes or the like fixed to each side of the boiler and laterally outward thereof whereby as the boiler is tilted due to ship roll a drop in water level in one tube will be accompanied by a corresponding rise in the other tube. Both tubes are adapted to influence the feed water supply so that a compensating effect is achieved with a relatively small angular ship roll. However, since each tube is necessarily disposed a substantial distance from the vertical center line of the boiler considerable fluctuation in tube water level results and with considerable angular roll the tubes may be emptied or completely filled. Practical considerations limit the height or extent of the tubes and it is apparent that if the water level is extended beyond the tube limits that the control of the feed water will be erratic.

It is a primary object of my invention to provide improved feed water regulating apparatus for boilers.

Another object of my invention is to provide feed water regulating apparatus for boilers and which is particularly adapted to marine boilers whereby an accurate control of the feed water will be maintained responsive to the steam demands despite considerable angular roll of the ship.

Another object of my invention is to provide improved feed water regulating apparatus for boilers which can be easily installed on a conventional boiler and which is readily adjustable.

Other objects of the invention will be increas-

ingly apparent from a consideration of the following description and drawings.

According to the invention, a generally V shaped tube adapted to expand and contract under thermal change is mounted externally of the drum head of a boiler with the apex of the tube being disposed substantially on the vertical center line of the boiler and the tube arms extending at substantially equal angles at each side of the center line. The apex of the tube is fixed and ends of the arms are free to move under thermal change. Each of the arm ends is connected to separate rock levers which are pivoted laterally of each arm. One of the rock levers is adapted to operate the feed water valve in accordance with lever movement and the levers are inter-connected by link means whereby expansion of one arm a given amount and contraction of the other arm an equal amount will effect no change in the position of the feed water valve. The apex of the tube and the arm ends are connected to the boiler whereby in a stationary boiler the length of each arm will at all times be substantially the same, and will be determined by the boiler water level.

When employed on a marine boiler one arm will expand in accordance with the amount the boiler is tilted from a normal position and the other will contract but the composite action will not materially effect the position of the feed water valve. Due to the normal water level in each arm being only a short distance laterally from the vertical center line of the boiler the water level only fluctuates through relatively small distances despite considerable angular roll of the ship and well within the tube limits so that an accurate control of the feed water is maintained.

In the following description and drawings:

40 Fig. 1 is a plan view of the end portion of a boiler drum and my improved regulating apparatus,

45 Fig. 2 is an end elevational view of the apparatus illustrated in Fig. 1,

45 Fig. 3 is an enlarged sectional view of part of the apparatus shown in Fig. 2 taken along line 3—3 of Fig. 4 and

50 Fig. 4 is a side elevational view of the apparatus of Fig. 3.

50 Referring now to the drawings, and particularly Figs. 1 and 2 I have indicated a boiler drum at 10 and the drum head at 11. The feed water supply line 12 connects with a feed water valve 13 and the valve is connected to a line 14 communicating with the lower portion of the boiler

drum. The particular type of valve used constitutes no essential part of the present invention but I preferably employ a valve of the piston type wherein a rotatable lever shaft 16 is disposed eccentrically of the line of piston movement and through suitable internal link means the piston lift and flow of feed water is controlled by the relative rotary movement of shaft 16. The outer or right hand end of lever 16, as viewed in Figs. 1 and 2, is locked to an L shaped lever 17 having a horizontally extending arm 18 and a depending arm 19. The lower end of arm 19 is connected to a tension spring 21, the opposite spring end being secured to a bracket 22 whereby spring 21 will continuously urge lever 16 in a direction to open the valve.

The regulating apparatus will now be described. A pair of brackets 23 secured to line 14 support a generally triangular shaped frame 24. Frame 24 may comprise a pair of spaced members 26 of channel cross-section and preferably formed of iron or a material unaffected by thermal change. However, since the frame 24 is installed in a zone of relatively constant temperature it may be made of any suitable material as its dimensions remain practically constant. Mounted between frame members 26 is a thermostatic tube 27 of inverted V form, the apex of tube 27 being positioned in frame 24 by a Y element 28 supported by a spacing plate 31 disposed between members 26 and adjusting nuts 30. The arms of tube 27, indicated at 32 and 33 are sealingly secured to element 28 and are inclined at substantially equal angles. Arms 32 and 33 are of substantially equal length and frame 24 is mounted to dispose the apex of tube 27 at the vertical center line of the boiler drum and the horizontal center line of the arms slightly below the normal water level of the boiler.

A rock lever 34 is mounted between frame members 26 to rotate about an axis 36 and is pivotally connected to tube arm 33 as indicated at 37 whereby lever 34 will be rocked as arm 33 contracts and expands. A second rock lever 38 mounted in a similar manner is adapted to be rocked by thermal change in arm 32 and it will be noted that when both arms expand the rock levers are moved towards each other and when both arms contract the rock levers are moved away from each other. An L shaped lever 39 is pivotally connected to the upper end of rock lever 34 as shown at 41. A pair of link arms 42 are pivotally connected to the upper end of rock arm 38 and at the opposite ends are adjustably and pivotally connected to lever 39. A strut 43 is adjustably and pivotally connected to a horizontally extending part of lever 39 and at the lower end is pivoted to the outer end of arm 18 of lever 17. Strut 43 is provided with tension relief means 44.

The operation of the apparatus so far described will now be explained. Assuming the apparatus to be used on a stationary boiler or a marine boiler disposed parallel to the fore and aft center line of the ship and that the ship is riding at an even keel, the thermostatic tube 27 is connected at the apex with the steam space of the boiler through a line 46 sealed to element 28 and the lower ends of arms 32 and 33 are connected with the water space of the boiler through a conduit 47 so that the water level in each arm will be the same and will correspond with the boiler water level. Upon a decrease in boiler water level there will be a similar decrease in each arm and an increase in the amount of steam in each arm causing both arms to expand an equal amount where-

upon rock arm 38 will be rotated in a clockwise direction and move lever 39 in a clockwise direction. Rock lever 34 will move in a counter-clockwise direction and further move lever 39 in a clockwise direction. Thus, strut 43 is moved downwardly and this movement is aided by tension spring 21 causing lever 17 and shaft 16 to open the valve. An increase in boiler water level causes a reverse action but in each instance the action of the arms of the thermostatic tube on lever 39 is cumulative rather than opposed.

It will be noted that tension spring 21 is the source of power for opening the feed water valve when the water level falls. Further, spring 21 maintains the whole system in tension and thereby takes up the slack at the pin-connected points and keeps adjusting nuts 30 tight against the plate 31. Of course, slack in the system could be prevented by disposing adjustable support means beneath Y element 28 and weight or spring load the thermostatic tube 27 at its apex to maintain the tube arms under compression.

The relative effect of the rock arms on lever 39 may be altered by connecting link arms 42 at different holes 40 and the amount of valve movement for a given movement of lever 39 may be altered by connecting strut 43 at different holes 45.

If the apparatus is used on a marine boiler and the ship is rolling the water level in each arm 32 and 33 will alternately rise and fall since frame 24 is fixed to and will move with the boiler. As the boiler is tilted in a clockwise direction arm 32 will be raised and the water level therein will be lowered causing the arm to expand and resultantly lever 39 will tend to move in a clockwise direction. However, arm 33 will be lowered causing the water level therein to increase thereby contracting the arm and tending to move lever 40 39 in a counter-clockwise direction with the net result that lever 39 is not appreciably effected by ship roll and an accurate control of the feed water is maintained. If the normal boiler water level is indicated by line L it will be noted that the distance D from the vertical center line of the drum to the water level in the thermostatic tube arms is relatively small and that if the angular roll of the boiler is considerable as indicated by the line L' that the fluctuation in water level in the arms is relatively small and well within limits which would completely empty or fill either arm.

Although I have shown and described a preferred embodiment of my invention I contemplate that numerous and extensive departures may be made therefrom without departing from the spirit of my invention and the scope of the appended claims.

The invention is hereby claimed as follows:

1. Feed water regulating apparatus for boilers comprising a boiler drum, a generally V shaped thermostatic tube having its apex fixed to the drum head substantially at the vertical center line thereof and its arms inclined at substantially equal angles to said center line, the arms being substantially equal length and the arm ends remote from the tube apex being freely movable under thermal change, the tube being connected to the steam space and water space of the boiler at the apex and arm ends whereby the arms will expand and contract in accordance with the relative amount of steam and water therein, the tube apex connection forming a fixed common communicating means for both arms with the boiler a feed water valve, means for actuating the valve,

and link means connecting each of said arm ends with the actuating means whereby the valve will be actuated in correspondence with the composite movement of both arm ends under thermal change.

2. The feed water regulating apparatus as described in claim 1 and wherein the link means comprises a pair of rock levers each movable by a different arm, and a third lever operatively connected to the valve and pivotally connected to each of said rock levers at spaced points.

3. Feed water regulating apparatus for boilers comprising a boiler drum, a triangular frame of material relatively insensitive to thermal change having its apex at the vertical center line of the drum and arms extending at substantially equal angles to said center line, a generally V shaped thermostatic tube having its apex fixed to the

frame apex and its arms nested in the frame arms, a pair of rock levers pivoted on the frame and each being movable by a different tube arm under thermal change, the tube being connected at the apex and arm ends to the steam and water space of the boiler whereby the water level in each arm will correspond to boiler water level, a feed water valve, a third lever operatively connected to the valve and pivotally connected to the rock levers at spaced points whereby the third lever may be independently moved by either rock lever, and the levers being arranged so that when the boiler is in normal position the effect of the rock levers upon the third lever is cumulative upon a change in boiler water level and when the boiler is suddenly tilted the effect of the rock levers upon the third lever is opposite.

WM. L. HUNTER.
